UNITED STATES PATENT OFFICE.

JOSEPH P. LISK, OF MACEDON, ASSIGNOR OF TWO-THIRDS TO GILBERT F. EVERSON AND LOUIS P. ENGEL, OF PALMYRA, NEW YORK.

VALVE FOR STEAM-ENGINES.

SPECIFICATION forming part of Letters Patent No. 394,930, dated December 18, 1888.

Application filed May 12, 1888. Serial No. 273,650. (No model.)

To all whom it may concern:

Be it known that I, JOSEPH P. LISK, of Macedon, in the county of Wayne and State of New York, have invented a new and useful Improvement in Valves for Steam-Engines, which improvement is fully set forth in the following specification and shown in the accompanying drawings.

My invention relates to the manner of letting steam into and out of the steam-cylinders; and the object is to construct the valve and ports in such a manner that steam will be admitted from the steam-chest into the cylinder through two independent openings at each end of the cylinder and out through the same in the act of exhausting, the valve being perfectly balanced as to the action of steam upon it.

The invention is hereinafter more fully described, and particularly pointed out in the claim.

Referring to the drawing, Figure 1 is a view at the end of the cylinder, the latter, with the steam-chest, being transversely sectioned, as on the line xx in Fig. 2 and viewed as indicated by the arrow pointed thereon; Fig. 2, a longitudinal section of the cylinder and steam-chest, taken as either on the upper or lower dotted line yy in Fig. 1 and viewed as indicated by either of the arrows pointed on said respective lines, both views being exactly alike; Fig. 3, a transverse section of the parts, taken on the dotted line zz in Fig. 2 and viewed in the same direction as Fig. 1; Fig. 4, a longitudinal section of the steam-chest, taken on the dotted line x' in Fig. 1 and viewed as indicated by the arrow pointed on said line; Fig. 5, a view of one of the equal faces of the valve, a part being broken away; and Fig. 6, a view taken at the end of the valve.

Referring to the parts shown, A is the cylinder of a steam-engine, and B the steam-chest.

C is a valve within the steam-chest, and a the valve-rod. The steam-chest contains within it two valve-seats, b b, both alike and opposite each other, as shown, said valve-seats each being pierced by inlet and exhaust ports c c and d, substantially of common form. The four inlet-openings of the two valve-seats communicate with the interior of the cylinder

through four separate ports, e e, by means of side pipes, f f. The exhaust-port in each valve-seat leads into a passage, g, which passages unite at h in a common exhaust or exit opening for the cylinder.

The valve is formed with two similar oppositely-turned faces, i i, to meet the respective valve-seats b b to open and close the various ports, as hereinafter more fully explained. It will be seen from Fig. 4 that two inlet-openings for live steam to one end of the cylinder are made simultaneously by the valve, the two currents of steam flowing therein entering the same end of the cylinder, but upon opposite sides thereof. It will also be seen that the exhaust-steam from the opposite end of the cylinder has two passages out from the cylinder open to it at the same time by the valve. By this construction twice the area of opening is formed for the inflow of steam to either end of the cylinder for the same amount of travel of the valve in making either its forward or backward movement. This is important, for the shorter the travel of the valve the less is the power of the engine taxed to drive it.

Both of the working-faces of the valve being equal and equally acted upon by the steam at any given moment, the valve is perfectly balanced so far as the action of the steam upon it is concerned. I make the valve in two equal parts, k k, and bolt them together, as shown, back to back. The valve-rod is provided with a longitudinal conical piece, l, fitted to a conical opening formed one-half in each of said parts k k of the valve. This cone acts as a spreader for the two halves of the valve, by means of which they may be set apart to meet more closely the opposing valve-seats b b, to compensate for the wear of the same. Collars n n are secured to the valve-rod by set-screws or other similar and well-known means—one on each side of the valve. One of these collars bears against the large end of the cone, while the other one bears directly against the side of the valve. By this means the cone is held relatively to place when the halves of the valve have been properly adjusted to the valve-seats.

The valve-rod passes through a stuffing-box, D, of common form in the side of the steam-

chest, and the live steam from the boilers enters the steam-chest through an opening, E, conveniently formed and of the usual kind.

The opening *h* for the exit of the steam from the cylinder is formed in a cap or dome, F, secured to the open side of the steam-chest. To this cap the exhaust-pipe is secured in the usual manner.

What I claim as my invention is—

10 A steam-engine formed with similar parallel and opposing valve-seats, each having inlet-ports communicating with the interior of the cylinder, and an exhaust-port, in com-

bination with a valve for the seats, a valve-rod passing through the valve, the latter being 15 divided on a plane parallel with the valve-seats and on the axis of the rod and formed with a longitudinal conical cavity, one-half in each, a conical sleeve shorter than the valve in said cavity upon the rod, and retaining- 20 collars on the rod on each side of the valve, substantially as shown.

JOSEPH P. LISK.
